(57) **CLAIM**

The ornamental design for a fabric scarf pin as shown and described.

DESCRIPTION

FIG. 1 is a front right perspective view showing a fabric scarf pin, together with a pin backing that constitutes a single, unified piece;

FIG. 2 is a back left perspective view thereof;

FIG. 3 is an partial enlarged view of FIG. 2;

FIG. 4 is a front view of FIG. 1;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an environmental view illustrating the fabric scarf pin on a jacket lapel.

The broken lines in FIGS. 2–3 represent the bounds of the partial enlarged views and form no part of the claimed design. The broken lines shown in FIG. 10 depict environment and form no part of the claimed design.
